United States Patent Office.

HARRIET S. MALTBY, OF CINCINNATI, OHIO.

Letters Patent No. 94,227, dated August 31, 1869.

IMPROVED PASTRY-ROLLER.

The Schedule referred to in these Letters Patent and making part or the same.

To all whom it may concern:

Be it known that I, HARRIET S. MALTBY, of Cincinnati, county of Hamilton, and State of Ohio, have invented a new and useful Machine for Rolling Pastry; and I do hereby declare that the following is a full, clear, and exact description of the same, reference being had to the accompanying drawings, and to the letters of reference marked thereon, in which—

Figure I is a perspective view of the whole machine as ready for use, and

Figures II and III, cross-sections, showing the peculiar structure of the reversible apron.

The nature of my invention is the application of pastry-rollers to a common table, by means of a suitable frame-work, adjusted by sliding boxes at the ends, and a reversible apron, for holding pastry, and capable of clearing the rollers of adhering pastry, when necessary.

The main frame of the machine, shown in Fig. I, is marked F, and may be made of wood, iron, or other material.

J, the bottom piece of the frame, is a jaw, furnished with a thumb-screw, for fastening to the table;

R R are the rollers, provided with cog-wheels, giving the motion that molds the pastry; and

C, the crank.

A marks the reversible apron, passing through the guide G, held by a regulating thumb-screw.

The edge of the apron next the rollers is bevelled as shown in Figs. II and III.

When pressed to the roller, as in Fig. II, it clears it from adhering pastry, and reversed, as in Fig. III, it acts, in a similar manner, upon the other.

At each end of the upper roller is a sliding box, marked B, to which the end of the thumb-screw above it is fastened. The box is lifted or lowered by turning this screw. These two sliding boxes, in this way, gauge this upper roller, adapting the space between it and the lower to the kind of work required.

I do not claim as new the use of rollers set in a frame, or anything in the general structure of the machine; but

What I do claim as my invention, and desire to secure by Letters Patent, is—

The combination of the reversible apron A with the guide G, the rollers R, the frame F, and the jaw J, all arranged as and for the purpose specified.

In testimony of which invention, I hereunto set my hand, this 25th day of February, 1869.
